(57) CLAIM

The ornamental design for a sleepwear set, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of a sleepwear set showing the claimed design.

FIG. 2 is a back view thereof.

FIG. 3 is a right side view thereof.

FIG. 4 is a left side view thereof.

FIG. 5 is a front view thereof, shown in an alternative wearing configuration, with the waistband of the pants of the sleepwear set folded downward, doubled over and overlaid, inside-out, onto the front surface of the pants of the sleepwear set; and,

FIG. 6 is a rear perspective view thereof, shown in an environment of use.

The “LUNYA” trademark and logo incorporating the same in the drawings and forming a part of the disclosure are trademarks of Lunya Company.

The broken line outline of the partial human figure and slippers in FIG. 6 assists in illustrating how the sleepwear set may appear when in a position of use, but forms no part of the claimed design. The broken lines of the sleepwear set depict portions and features of the article that form no part of the claimed design.
